UNITED STATES PATENT OFFICE.

AUGUST Q. MUELLER AND WALTER H. KOELLER, OF MILWAUKEE, WISCONSIN.

MANIFOLD-HEATER.

1,399,980.

Specification of Letters Patent. Patented Dec. 13, 1921.

Application filed December 29, 1920. Serial No. 433,789.

To all whom it may concern:

Be it known that we, AUGUST Q. MUELLER and WALTER H. KOELLER, citizens of the United States, residing at Milwaukee, county of Milwaukee, and State of Wisconsin, have invented new and useful Improvements in Manifold-Heaters, of which the following is a specification.

This invention relates to manifold heaters 10 for internal combustion engines.

Objects of this invention are to provide a manifold heater which may be readily placed about the vertical portion of the manifold; to provide a heater having a fire 15 container in the lower portion thereof so related to the vertical portion of the manifold that the heated gases generated during combustion may pass upwardly about such manifold, and quickly raise the temperature 20 thereof to the desired extent; and to provide a manifold heater adapted to receive solid fuel, such, for example, as solidified alcohol, cardboard impregnated with salt-peter, or other similar prepared fuels.

Further objects of this invention are to 25 provide a jacket and fire pot for a manifold so constructed that they may be stamped from sheet material, and may subsequently be readily shaped to conform to the manifold; 30 to so form these stampings that portions thereof may be bent so as to resiliently and frictionally engage the manifold at one point to properly position the heater, and at another point to positively engage and lock 35 upon a portion of the manifold; and to form these stampings of thin, lightweight material, thereby materially reducing the weight and correspondingly preventing rattling, as the momentum acquired during vibratory 40 motions is extremely slight.

Further objects are to so relate a heater and manifold that the manifold may be quickly heated even in the coldest weather to a temperature sufficient to insure the 45 ready starting of the motor; and to so proportion and arrange the parts that solid fuel of a predetermined heat generating value may be used, thereby avoiding an uncontrolled flame or an excessive generation 50 of heat.

Embodiments of the invention are shown in the accompanying drawings, in which:

Figure 1 is an elevation showing the manifold of an internal combustion engine 55 with the heater applied thereto, parts being broken away for clearness.

Fig. 2 is a section on the line 2—2 of Fig. 1.

Fig. 3 is a view of the blank from which the major portion of the heater is formed. 60

Fig. 4 is a view of the blank from which the fire pot is formed.

Fig. 5 is a fragmentary view corresponding to Fig. 1 and showing a further form of the invention. 65

The manifold has the usual horizontally extending portion 1, the vertical portion 2, and the laterally extending neck portion 3, at which latter point, the carburetor is usually attached. About this vertical portion, the heater is positioned, such heater comprising a main casing 4 formed from sheet material and wound about the vertical portion. It is provided at its upper edges with inwardly directed prongs 5 which resiliently engage the vertical portion 2 of the manifold. It is further provided with an opening 6 through which the neck portion 3 of the manifold extends. The lower portion of the casing is closed by a fire pot 80 or container 7 which is cup-shaped and is provided with a heat insulating lining 8. This cup-shaped portion is equipped with downwardly projecting tongues 9 which engage over the edges of the heat insulating lining and retain such lining in position. The bottom portion of the casing is provided with inwardly directed tongues 10 which support the cup in position within the casing and is further provided with inwardly struck tongues 11 which engage the upper edge of the cup, and together with the lower tongues 10, securely position the cup within the casing. The lower portion of the casing 85 is provided with an opening 12 through which solid material may be inserted and through which the igniting match may be passed. 90

In the operation of the device, solid fuel, such as solidified alcohol, cardboard impregnated with saltpeter, or any other similar prepared fuel may be inserted through the opening 12. This solidified fuel is then ignited and the hot gases from the resulting combustion will pass upwardly around the 105 vertical portion 2 of the manifold and rapidly raise its temperature to the required degree.

This manifold heater may be readily formed from stampings, such for example, 110 as shown in Figs. 3 and 4. The blank from which the vertical casing 4 is formed is sub-

stantially rectangular in outline and is provided at one end with a plurality of outwardly projecting tongues 13 and adjacent the other end with upwardly pressed tongues 14 which together coöperate to lock the casing in its rounded form about the manifold. A rounded notch 15 is provided adjacent each vertical edge of the blank and such notches together coöperate to lock about the laterally extending neck portion 3 of the manifold. The tongues 5, 10, 11 and 14 may be readily formed during the stamping operation. The blank 7 from which the fire pot is formed may also be stamped with a plurality of outwardly projecting tongues 9 which may readily be formed at one operation.

Fig. 5 discloses a modified form of the invention in which a single casing member 16 is employed. In this form, tongues 17 correspond to the tongues 5 and resiliently engage the vertical portion 1 of the manifold and a pair of notches form an opening 18 corresponding to the opening 6 which lock about the laterally extending neck 3 of the manifold. This casing is formed from a blank in the same manner as the casing previously described and is provided with interlocking tongues 19 and 20 and inwardly directed lower tongues 21 which latter partially close the bottom of the casing. Solid fuel, such as cardboard impregnated with saltpeter, for instance, or other prepared fuels of this type may be inserted through an opening 22 and may rest upon the inwardly projecting tongues 21. This fuel is ignited and the heated gases pass upwardly around the vertical portion 2 of the manifold quickly raising its temperature to the desired extent. Obviously the resulting ash may eventually be discharged through the bottom of the casing between the inwardly projecting tongues 21.

We claim:

1. In combination an internal combustion engine manifold, a heater therefor, comprising a casing encircling the vertical portion of the manifold and spaced therefrom, resilient means for supporting the upper end of the heater in spaced relation to the manifold and engaging the manifold at a plurality of points completely around its periphery while allowing the gases of combustion to pass between such spaced means, and a bottom cup-shaped portion closing the lower end of the casing.

2. In combination, an internal combustion engine's manifold having a vertical portion and a laterally extending neck in communica-

cation therewith, and a heater for said manifold comprising a casing formed from flat sheet material wound about said manifold and positively locking about said neck portion, and means for supporting the upper end of the heater from the manifold at intervals to hold it in spaced relation thereto while allowing the gases of combustion to escape on all sides, said heater having a bottom cup-shaped portion adapted to receive solid fuel.

3. In combination, an internal combustion engine's manifold having a vertical portion and a laterally extending neck in combination therewith, and a heater comprising a casing surrounding said vertical portion and provided with inwardly directed tongues engaging said vertical portion to properly space said casing therefrom and having an opening through which said laterally extending portion of the manifold projects.

4. A heater for an internal combustion engine's manifold having a vertical portion and a laterally extending portion forming an elbow joint therewith, said heater comprising a casing formed of stamped thin sheet material and adapted to be wound about said vertical portion, interengaging securing means formed integrally with said casing and upon opposite sides of the meeting edges thereof, and a pan portion formed of stamped sheet material positioned within the lower portion of said casing, said casing having inwardly projecting tongues engaging and supporting said pan portion.

5. A heater for an internal combustion engine's manifold having a vertical portion and a laterally extending neck, said heater comprising a casing formed of sheet material having notched edges adapted to be positioned about said vertical portion with the notches in engagement with said neck, and a pan-shaped bottom portion positioned within and closing the lower end of said casing.

6. A heater for an internal combustion engine's manifold having a vertical portion and a laterally extending neck, said heater comprising a casing formed of sheet material having notched edges adapted to be positioned about said vertical portion with the notches in engagement with said neck, a pan-shaped bottom portion positioned within and closing the lower end of said casing, and a heat insulating lining for said bottom portion.

AUGUST Q. MUELLER.
WALTER H. KOELLER.
